AUTOMOBILE GOVERNOR

John W. Horine, Wilmington, Del.

Application December 13, 1935, Serial No. 54,343

2 Claims. (Cl. 175—355)

This invention relates to electrically operated speed regulators in general; and particularly, to an electrically operated speed regulator for internal combustion engines and other power developing and power utilizing units, to prevent the operation of such engines or units beyond a predetermined speed.

The main object of the invention is to provide a means for regulating or controlling the maximum speed of operation of an internal combustion engine or similar device, by a system of electrical devices which involve a minimum of extra equipment for the engine, but which are adapted for operation when the engine reaches a predetermined maximum speed to effect a stoppage in the further operation of the engine, and to prevent operation of the engine at any time in excess of a selected maximum speed.

Another object of the invention is to provide a mechanism of the character described which can be sealed by proper authorities in such position as to prevent the operation of an internal combustion engine, or an automobile driven thereby, beyond a lawful predetermined maximum speed.

Other objects of the invention will become apparent as the detailed description thereof proceeds.

In the drawings:

Figure 1 is a fragmentary side elevation of an internal combustion engine, such as is commonly used on motor vehicles, with the several parts of this invention illustrated in elevation;

Figure 2 is a top plan view of a control box forming part of the apparatus involved in this invention;

Figure 3 is a fragmentary elevation of the setting mechanism for predetermining the maximum speed of operation of the engine provided with this attachment;

Figure 4 is a diagrammatic lay-out of the apparatus as applied to the air intake of the internal combustion engine under control;

Figure 5 is a speed-voltage diagram relating to the speed control mechanism illustrated in Figures 1 to 4;

Figure 6 is a diagrammatic lay-out illustrating another form of the invention; and

Figure 7 is a speed-voltage diagram relating to the lay-out shown in Figure 6.

Referring to the drawings, in which similar parts are designated by like numerals:

The invention illustrated in Figures 1 to 5 of the drawings comprises a control box 8 suitably secured to the chassis C in position to control

the operation of a choke valve forming part of the carburetor 9 connected to the intake manifold 10 of an internal combustion engine designated generally by the reference character E.

The choke valve 11 (see Figure 4) is pivoted 5 in the air intake 12 of the carburetor; and, has its pivot pin 13 extended through the intake to be secured to a choke operating lever 14. The lever 14 is pivoted at one of its ends to one end of a link 15, the other end of which is pivoted by 10 means of the eyelet 15' secured to the upper end of a solenoid plunger arranged within the solenoid winding 17.

The other end of the lever 14 has a stud 18 mounted to rotate thereon about an axis perpendicular to the lever 14. The stud 18 is bored to receive slidably a manually operable choke rod 19. A collar 20, slidable on the end of the choke rod 19 where it projects through the bore of the rotatable pivot 18, may be secured in adjusted 20 position on said rod by means of a set screw 21. The object of this construction is to permit manual control, through the rod 19, of the choke at all times, without interfering with the automatic operation of the choke valve 11 by the solenoid 25 mechanism. A tension spring 22 has one of its ends secured to the top 23 of the solenoid framework, and has its other end secured to the choke lever 14 at a point so located as to hold the lever 14 in position to maintain the choke valve 30 11 normally open.

One end of the solenoid 17 is connected by a wire 24 to a terminal 25, and wire 26' through the switch 26 to the battery B. The other end of the solenoid 17 is connected by a wire 27 to a contact screw 28 which in turn, is connected by a wire 29 to a contact screw 30 adjustable on a supporting bracket 30' fixed to but insulated from the grounded base plate 31. The contact 30 is positioned in the path of movement of a 40 spring armature 32, suitably secured at one end to an angle bracket 33 fixed to the grounded base plate 31. It will be apparent from Figure 4 of the drawings that the armature 32 is constructed so as to be normally held with its free end in 45 yielding contact with the adjustable contact 30.

An electromagnet 34 is suitably secured to the base plate 31 in position to have its core 35 attract the armature 32 from contact closing position, whenever the aforesaid magnet is energized 50 by a current sufficiently strong to overcome the resistance offered by the spring construction of the armature. The magnet 34 is grounded at one of its terminals by means of the wires 36 and 36' connected to the ground contact screw 37. The 55

other terminal of the electromagnet 34 is connected by a wire 38 to one terminal 39 of an adjustable selector rheostat designated generally by the reference character R.

5 The rheostat R is of the well-known type including an annular resistance coil 40 over which the free end 40' of a selector arm 41 is adapted to be moved in yielding contact therewith. The arm 41 is pivoted to rotate about a pivot 42 extending upwardly from the center of the base of the rheostat, and is adapted to be held in an angularly adjusted position on the pivot 42 by means of the set screw 43. The pivot 42 is in conducting contact with the arm 41 and also with the bar 44 extending radially from the pivot 42 into conducting contact with the other terminal 45 of the rheostat coil 40.

10 The terminal 45 of the rheostat is connected by a wire 46 to the exciter terminal 47 of a generator 20 G forming part of the mechanism of the internal combustion engine. The other terminal 48 of the generator is connected by a wire 49 through the cutout 50' to the ungrounded side of the battery B.

15 The speed control mechanism as so far described, is operated by current derived from an automobile generator, and is dependent for its control operations upon the characteristics of a generator of this type. The diagram shown in 25 Figure 5 illustrates a characteristic speed-voltage curve of such a generator, the speed being in miles per hour of the car, and the voltage that from the third or exciter brush 47 of the generator to ground. In connection with the description 30 of this form of the invention, the word "voltage" refers to this third brush to ground voltage.

Let:

R_c = Speed relay magnet coil resistance.

40 R_s = Speed selector rheostat resistance, S M. P. H. setting.

R_{45} = Speed selector rheostat resistance, 45 M. P. H. setting.

V_s = Third brush voltage at S M. P. H.

45 V_{45} = Third brush voltage at 45 M. P. H.

I_{40} = Current in coil of speed relay at 40 M. P. H.

I_{45} = Current in coil of speed relay at 45 M. P. H.

50 I_r = Current in coil of speed relay when armature e is released.

I_a = Current in coil of speed relay when armature e is attracted.

i = Current in coil of speed relay at any given instant.

55 v = Third brush voltage at any given instant.

Let us assume that the speed selector rheostat R is set for choke closing operation at 45 miles per hour. Then, the operation of this form of the invention, is as follows:

60 Closing the ignition switch 26 causes current to flow from the battery B through the solenoid 17, wires 27, 28 and 29, contact 30 and armature 32 to ground; thereby causing the plunger 16 to be sucked into the solenoid and close the choke 65 valve 11. This initial closing of the choke valve assists in starting the engine. After the engine has started, the generator excitation voltage builds up to about four volts (see Figure 5), causing the magnet 34 of the speed relay to attract the 70 armature 32, and thereby break the circuit through the solenoid 17. This break in the circuit permits the spring to effect opening of the choke valve 11.

Assuming, now, that the car is accelerated: 75 then, so long as the speed of the car is lower than

45 miles per hour, the generator voltage causes enough current to flow through the magnet 34 to attract armature 32 and break the circuit through the solenoid. In this condition the current at any given instant is always greater than when the armature is in circuit closing position.

The speed selector rheostat R is set at such resistance R_{45} , that when the voltage decreases to the value of 1.2 volts, the current through the magnet 34 is too weak to hold the armature 32 10 away from the contact 29. The circuit through the solenoid 17 is then closed and causes the choke valve 11 to move into closed position. The closing of the choke valve at the selected speed (in this instance, 45 miles per hour) slows down the motor and prevents the car attaining any speed in excess of the predetermined maximum of 45 miles per hour.

The air gap between the armature 32 and the magnet 34 is so proportioned that the car must 20 decelerate to a speed approximately 5 miles an hour below the setting of the relay R, before increase in generator excitation voltage will again cause a current to flow through the magnet 34 25 sufficient to attract the armature 32 and break the circuit.

In general, at any given speed S, this speed governor acts to close the choke valve in accordance with the equation,

$$I_s = \frac{V_s}{R_c + R_s} = I_r$$

Similarly, the governor acts so as to release and open the choke valve in accordance with the 35 equation,

$$I_{(S-5)} = \frac{V_{(S-5)}}{R_c + R_s} = I_a$$

The resistance of the wiring is assumed to be negligible.

The governor, then, can be set to operate at any speed from 20 to 65 miles an hour by properly proportioning the amount of resistance of the rheostat R which is inserted into the circuit of the magnet in the speed relay.

The shaft 42 of the rheostat R extends through the control box 8 and has a handle 50 secured to the end thereof. A flange 51 projects from the base of the handle 50, and is provided with a series of holes 52, each of which is adapted to register with a hole 53 formed in a clip 54 suitably fixed to the control box 8. Any suitable sealing means 55 can be used to lock the handle 50 and the rheostat arm 41, in any position corresponding to the maximum speed desired. The openings 52 may be considered as graduations reading against an index 56 on the wall of box 8, to assist in setting the relay for any desired maximum speed.

The foregoing description covers the operation of the governor as shown in Figures 1 to 5. If the governor is to be actuated by a small auxiliary generator or exciter, operating upon a rising voltage characteristic with increase of speed, the contacts of speed relay are arranged to be closed instead of opened by armature when attracted by the magnet, and resistance is added to the circuit of speed relay instead of cut out in order to obtain governor action at higher speed.

As shown in Figure 6, the choke valve operating mechanism is the same as in the form of the invention described above, and the parts thereof are designated by the same reference numerals. One terminal of the solenoid 17 is connected by

a wire 57, through the ignition switch 58 with the battery, and the field 59 of the auxiliary generator 60 is connected to the solenoid side of the ignition switch 58 and thence to the battery 5 when the switch is closed. The car generator 61 is connected through the cut-out 62 by wire 63 to the wire 57.

The speed relay, in this form, comprises the electromagnet 64 arranged to attract, when energized, the spring armature 65 which is suitably mounted and grounded on the support 66. When the armature 65 is attracted toward the magnet 64, a contact 67 on the armature closes the circuit through the solenoid 17 by means of the contact 68 at the end of a wire 69 connected to the other terminal of the solenoid.

The selector rheostat R' is the same, structurally, as the rheostat R; and has one terminal 70 connected by a wire 71 to a terminal of the electromagnet 64. The other terminal 72 of the rheostat is connected by wiring 73, through the auxiliary generator 60, to the other terminal of the magnet 64.

In this second form of the invention, the choke operating solenoid is operated only when the current through the auxiliary generator has increased sufficiently to energize the magnet 64 to close the contacts 67 and 68. In other words, this form of the invention becomes operative only 30 when the engine attains the speed for which the selector rheostat is set.

In the first form, the solenoid is operated at the start and also at the selected maximum speed. However, it is possible, in the first form, 35 to eliminate the automatic closing of the choke between the time when the switch is closed and the engine "catches", by taking the feed for the solenoid from the generator side of the generator cut-out.

40 In this specification and claims appended hereto, the device is described as operating the choke

valve of an internal combustion engine. However, it must be understood that the invention is not limited to use with the choke valve, since it is capable of being applied to the operation of the gas intake valve. It is to be understood that the invention is not to be considered in any way as limited to the precise details of construction described herein, nor limited in any other way except as indicated in the claims appended hereto.

What I claim is:

1. The combination of an internal combustion motor having valve mechanism movable to control the operation thereof and having means for holding said mechanism normally in inoperative position, with a generator geared to said motor, 15 and means operated by said generator to move and hold said mechanism in operative position against the resistance of said holding means during the generation of current from zero to a predetermined value, and means operated by 20 current in excess of said value to release said mechanism.

2. The combination with the normally open choke valve of an internal combustion motor, of a generator geared to said motor, a cut-out 25 connected to one of the terminals of said generator, a solenoid having one terminal connected through said cut-out to said terminal, and having its other terminal grounded, a plunger in said solenoid, operating mechanism connecting the plunger to said choke valve, yielding means for holding said mechanism normally in position to hold said valve open and the plunger withdrawn from the solenoid when deenergized, and means operated by said generator to energize said 30 solenoid during the generation of current from zero to a predetermined value, and means operated by current in excess of said value to deenergize said solenoid.

JOHN W. HORINE. 40
